UNITED STATES PATENT OFFICE

2,508,498

IGNITION SYSTEM ANALYZER

Hiram D. Currier, Chicago, Ill., assignor of one-half to Louis A. Bisson, Evanston, Ill.

Application March 27, 1947, Serial No. 737,458

14 Claims. (CL. 175—183)

1

The present invention relates to means for analyzing conditions in an ignition system, such as in a line from an ignition coil to a spark plug, by removing the lead to the spark plug and contacting the invention to such lead and to such spark plug, and also having a connection to ground, the novel means having an indicating means capable of indicating the condition or conditions in the ignition circuit, such as a leakage in the spark plug, in such a way as to give an analysis of the particular condition being analyzed, and having capacitors, resistance, and gap means so associated with the indicating means and the ground connection as to produce electrical effects in the indicating means in accordance with and as analytical of any abnormality in the ignition circuit, the indicating means indicating the kind or nature of such abnormality.

Another object of the invention is to provide a novel means that is self-contained and in the nature of a unitary device with a contact element, as a prod, for contact with an ignition circuit part or lead, normally running to the spark plug but disconnected therefrom when analyzing, and a pair of other contact elements, which may have suitable clip or clamping means for connection to ground and to the spark plug, all the parts, aside from the contact elements, being housed and sealed in a holder, and this holder having a novel means, as a window for affording visual reception of the effects produced in the indicating means, which may be a light or lamp of the neon type.

Another object of the invention is to provide a novel holder with novel means for assembling the parts of the unit in the holder, and also for sealing the holder from access of moisture, dust or the like, and for holding the parts firmly in a most convenient and self-contained arrangement for direct electrical effects without losses that would otherwise be present in a different arrangement, and yet very convenient of assembly when making up the device.

A further object of the invention is to provide a novel sight means for affording facile viewing of the indicating means when effecting an analyzing of the ignition circuit.

Other objects, advantages, capabilities, features and the like are comprehended by the invention as will later appear and as are inherently possessed by the invention.

Referring briefly to the drawings:

Fig. 1 is a diagrammatic view of the invention when connected in an ignition system for analyzing it;

2

Fig. 2 is a side view of a holder used in the invention;

Fig. 3 is a fragmentary sectional view, on an enlarged scale, of the sight means portion;

Fig. 4 is a longitudinal sectional view of the invention;

Fig. 5 is a similar sectional view at a normal to that shown in Fig. 4; and,

Fig. 6 is a transverse sectional view taken in a plane represented by line 6—6 in Fig. 5 of the drawings.

Referring more in detail to the drawings the embodiment selected to illustrate the invention is shown in connection with an ignition system which has an ignition coil comprising a primary 1, a secondary 2, a distributor 3, and a lead 4 normally connectable to a spark plug 5 by way of a lead connector 6. The present invention is connected in the circuit between the connector 6 and the spark plug 5 and comprises a prod 7 having a connector 8 connected to a spark gap means 9 in turn connected by way of a conductor 10 running to a common contact means 11.

From this common contact means 11 runs a conductor 12 to a capacitor 13 thence to conductor parts 14 and 15 and to ground 16, which latter may be the metal frame of the machine. This conductor part 15 may have a suitable type of spring clip or clamp means 17 (see Fig. 4) for connecting to the ground 16.

From the common contact means 11 also runs a conductor 18 to a resistance 19 connected by way of a conductor 20 running to the conductor 14—15, whereby the resistance 19 is in parallel with the capacitor 13.

From the common contact means 11 runs a conductor 21 by way of a capacitor 22 and conductor segments 23 and 24 running to the spark plug 5. The conductor 24 may have a suitable type of spring clip or clamp means 25 (see Fig. 4) for connecting to the spark plug 5.

From the common contact means 11 runs a conductor 26 to an indicator 27, which is preferably of the neon lamp type, this indicator having electrodes 28 and 29, the conductor 26 being connected to an electrode, as the electrode 28, and from the other electrode, as the electrode 29, runs a conductor 30 which is connected to the conductor segments 23 and 24.

The spark plug 5, as usual, has a connection to ground 31, which may be a part of the machine.

Referring to Figs. 4, 5, 2, 3 and 6 is shown a holder 32, of insulating material, in which the above-described parts are, in the main, housed. In an end portion of the holder 32 is force fitted or otherwise attached a disc 33, also of insulating

material, the peripheral edge of which fits closely in the end portion of the holder 32.

The prod 1 has a hollow shank or skirt 36 the open end of which is fitted firmly in a suitable hole or opening provided in the disc 35 so that an end of the conductor 8 extends into the shank or skirt 36 and also into the prod part 1 which has a small recess in which the end of the conductor 8 fits with a tight fit or may be otherwise fixed, as desired.

Spacedly within the end portion of the holder 32 from the disc 35 is press fitted or otherwise attached a flat piece 37, also of insulating material, of polygonal form so as to have corner portions 38 (see Fig. 6) which engage the wall of the holder 32, and has cut-out portions to provide holes 39, through one of which passes or extends the conductor 8. This piece 37 is for gathering and holding the extra length portion of the conductor 8 in the space between this piece 37 and the disc 35 to prevent such conductor from contacting with any of the parts of the means in the holder 32, such as from contacting the spark gap means 9 or some other conducting part, such as the conductor 23, or the like.

At and in the other end portion of the holder 32 is force fitted or otherwise attached a disc 42, also of insulating material, the peripheral edge of which fits closely in the end portion of the holder 32. In the disc 42 are provided suitable holes or openings in which fit suitable eye means or grommets 43 and 44 for the passage therethrough of the conductors 24 and 15, respectively, and the openings in these eye means or grommets are such as to closely fit with the conductors 24 and 15 to seal them so as to prevent entry of moisture, dust or the like, within the holder 32. These parts 43 and 44 also are preferably of insulating material.

Within the holder 32 is suitably supported a supporting piece or strip 40, also of insulating material, and on this strip 40 are suitably supported or carried various parts of the device, such as the lamp 21, the condensers 22 and 13, the resistance 19, and the common contact member or means 11, and suitable holes or apertures 41, 45 and 46 are provided for the passage or extension therethrough of the conductors 30, 12 and 21, and 14, respectively. See Figs. 4 and 5. At the upper end of the strip 40, as shown in Figs. 4 and 5, the spark gap means 9 is suitably carried or supported, as desired.

In the wall of the holder 32 is provided a window for viewing the lamp 21, this window comprising an opening or hole 47 (see Fig. 3) and over this opening is placed a transparent sheet 51 which may be of thin material, such as of any suitable material or mica, synthetic material, or the like. This sheet 51 is wrapped about the holder 32, as shown, and is suitably sealed to the holder 32 along the border portions of the sheet or wrapper 51, as indicated at 52 and 53 in Fig. 2. Hence, the wrapper 51 is sealed to the holder 32 to prevent entry of humidity, dust, or the like, as by way of the window 47. Since the wrapper 51 is of transparent material, that portion, as 54, of the wrapper 51 will permit transmission of light rays from the lamp 21 to be seen by the tester.

In operation or use the terminal clip 6 is disconnected from the spark plug 5 and the conductor 24 with its clip 25 is connected to the spark plug 5, and also the conductor 15 and its clip 17 is connected to ground 16. Thence, the prod 1 is contacted with the terminal 6. As the dis-

tributor 3 operates an electrical impulse passes through the device. The impulse is by way of the spark gap 9 and the condenser 13 as well as to the resistor 19, and to ground 16. It does not flow to or through the condenser 22, nor through the light 27, nor across the gap of the spark plug 5, because the potential is not sufficient to break down the spark plug gap, the energy having been absorbed through the path of the condenser 13 and the resistance 19, which are in parallel. On the other hand, if there be a leakage in the spark plug, as represented by, a resistance 55 (see Fig. 1), the potential across the spark plug terminals is sufficient to permit current to flow through the lamp 27 and cause it to glow, thus indicating a faulty spark plug. If the circuit is in proper condition the lamp 27 does not glow.

By way of example, for a successful operation of the device, the condensers 13 and 22 will have a value of 0.01 microfarad, and the value of the resistance 19 will be 5.6 megohms. That will measure leakage up to 22 megohms. The function of the spark gap 9 is to segregate the wiring of the testing equipment from the wiring of the ignition coil and the distributor after cessation of the distributor impulse. The resistance 19 is placed in the circuit, as shown in Fig. 1, in parallel with the condenser 13 so that this condenser may be discharged between impulses derived from the distributor 3 and thus be made available to absorb the next impulse, as previously described.

While I have herein described and upon the drawings shown an illustrative embodiment of the invention, it is to be understood that the invention is not limited thereto but comprehends other constructions, details, arrangements of parts, features or the like without departing from the spirit of the invention.

Having thus disclosed the invention, I claim:

1. An analyzer of the character disclosed in an ignition system having a source of ignition potential, a distributor, and a spark plug; the combination therewith of a spark gap means, conducting means including two segments for affording conductance from the spark gap means through two paths of conductance, one of said segments including a signal and a condenser both in series with the spark plug, and the other of said segments including a condenser and a resistance, and a ground connected to said latter condenser and resistance, of which said second path is for absorbing the potential charges when no leakage exists in the spark plug and said first path becoming operative to cause the signal to glow when leakage exists in the spark plug.

2. An analyzer as set forth in claim 1, and wherein said first mentioned condenser is in shunt with said signal.

3. An analyzer as set forth in claim 2 wherein said second mentioned condenser and said resistance are in parallel.

4. An analyzer as set forth in claim 3, and wherein is provided a common means of connection with which are connected conducting segments running to the spark gap means, to the signal and said first condenser, and to said resistance and to said second condenser.

5. An analyzer as set forth in claim 1, and wherein is provided a common means of connection with which are connected conducting segments from said spark gap means, said signal, said condensers, and said resistance.

6. An analyzer as set forth in claim 1, and wherein said signal is in the form of a neon lamp.

7. An analyzer as set forth in claim 1, and

wherein said second condenser may have a value of about 0.01 microfarad, and said resistance may have a value of about 5.6 megohms.

8. An analyzer of the character disclosed, comprising a hollow holder having an opening, closure means in said opening to seal the holder from entry of moisture and foreign matter, electrical conducting elements in said holder and extending through closure means to the exterior and being in sealing contact with said closure means, a supporting member in said holder, a spark gap means on said member, a signal lamp on said member, capacities on said member, a resistance on said member, one of said elements connected to said spark gap means, another of said elements connected to said lamp and to one of said capacities, a further one of said elements connected to said resistance and another of said capacities, and electrical conducting members connected from said spark gap means to said capacities, to said lamp, and to said resistance.

9. An analyzer as set forth in claim 8, and wherein is provided a common contact means on said support and wherein said electrical conducting members are connected to said common contact means.

10. An analyzer as set forth in claim 8, and wherein said holder has a window located opposite said lamp, said window having a transparency sealed to said holder.

11. An analyzer of the character disclosed, comprising a tubular holder having openings at its ends, closure members sealed in said openings, a prod extending through one of said closure members and sealed thereto, an electrical conducting element in said holder and connected to said prod, eyelets in said other closure member and sealed thereto, conducting elements in said holder and extending through said eyelets and sealed thereto, a supporting piece in said holder, a spark gap means on said piece, a signal lamp on said piece, capacities on said piece, a resistance

on said piece, said first-mentioned element connected to said spark gap means, of said second-mentioned elements one is connected to said lamp and to one of said capacities, and another is connected to said resistance and to another of said capacities, and further electrical conducting elements connected to said spark gap means, to said capacities, to said lamp, and to said resistance.

12. An analyzer as set forth in claim 11, and wherein is provided a common contact means on said piece and wherein said last-mentioned conducting elements are connected to said common contact means.

13. An analyzer as set forth in claim 12, and wherein said holder has a window located opposite said lamp, said window having a transparency sealed to said holder.

14. An analyzer as set forth in claim 12, and wherein is provided a window opening opposite said lamp, and a transparent sheet is wrapped around and sealed to said holder and extends over said window opening.

HIRAM D. CURRIER.
